RAZOR BLADE HANDLE ATTACHMENT

Eugene B. Miller, Chicago, Ill.

Application July 3, 1950, Serial No. 171,963

3 Claims. (Cl. 30—335)

1

My invention relates to razor blade handle attachments.

An important object of my invention is to provide a handle for removably and interchangeably securing razor blades thereto of the type that are used in ejector razors; the blade being a long, narrow type of blade having one cutting edge and one dull edge.

A further important object of my invention is to provide a handle having means whereby the cutting edge of the blade is nicked by pressure exerting and locking means so that the same will be held firmly in place.

A further object of my invention is to provide locking edge means on a locking tumbler which is urged into pressure relationship by a pressure locking screw; the said locking tumbler being provided with key means operating in keyway means in the said handle structure in order to guide the same and maintain it in transverse relationship to the cutting edge of a blade inserted into the handle structure.

A still further object of my invention is to provide a handle attachment for razor blades of the aforementioned character which is simple in construction and which can be manufactured economically in quantities.

Other objects, and ancillary advantages, inherent in my invention will become apparent from an examination of the accompanying drawings, bearing further elucidation in the ensuing description; wherein like symbols are used to designate like parts, and in which:

Fig. 1 is a front view of my invention with certain portions thereof broken away in order to more clearly indicate, or illustrate, the elemental structure thereof.

Fig. 2 is a transverse cross-sectional view taken substantially on the lines 2—2 of Fig. 1.

Fig. 3 is a cross-sectional view taken substantially on lines 3—3 of Fig. 1.

Fig. 4 is a front view of the locking tumbler means showing its structure in detail.

Fig. 5 is a slightly modified form of my invention wherein spring pressure means is utilized in preference to screw pressure means.

Referring to the various views, my invention is generally designated 6 and consists of two handles 7 having rounded portions 8 at one end, and being secured in place by suitable screws or fastenings 9.

The forward part of the handle is provided with a recess 10 resulting from the particular structure of the two handle sections as indicated in Fig. 2. One handle section 8 has a lip portion

2

19, a lip portion 21, an intermediately and recessed portion 20. The other handle 7 has complementary cuts 29 and 30 in order to match the extensions 19 and 21, and a raised portion 18 substantially centrally thereof in alignment with the recessed portion 20 on the other handle. Thus a narrow recess 10 is formed which will hold a blade generally designated 11 and having its cutting edge at 12. The rear edge thereof being dull as indicated in the cross-sectional view in Fig. 2.

The blade 11 is inserted into the space or recess 10, one handle element 7 being provided with a threaded portion 13 in order to receive the clamping screw 16, which is preferably formed with an enlarged knurl-headed portion 22, to permit clamping and loosening the said screw 16 by the fingers.

The said screw forces into place the locking 20 tumbler designated 15, which has two facets 33 terminating in a binding edge 15'. The said binding edge 15' is placed in transverse relationship to the cutting edge 12 of the blade. The tumbler is confined to vertical movement when the pressure screw 16 is applied thereto, and is held in guiding alignment by virtue of the keyway 14 in which the key 31 operates. Thus when pressure is applied to the screw the edge 15' will engage the edge 12 and nick the same as indicated at 17 thus holding the razor blade 11 firmly in its grip and locking engagement within the handle 7.

The modified form indicated in Fig. 5 is provided with an additional recessed portion 23 merging with the guide opening and key-way for the locking tumbler 32. This locking tumbler 32 is identical in construction with the one designated 15, and is provided with a semi-cylindrical equalizing portion 26 at its bottom for engagement by the locating bent portion 25 in the spring. The spring 24 is of suitable length and is anchored by the rivets 27 within the recess 23. The spring 24 is also provided with a pull portion 28 so as to permit flexing the spring downwardly when it is desired to remove the blade 11.

In order to place a blade in assembly, the blade is slipped in as shown in Fig. 1 and the screw 16 is tightened nicking the blade and holding it securely in place. In order to insert or remove a blade from the modified structure indicated in Fig. 5, the spring portion 28 is grasped and the plunger is allowed to drop out of engagement with the blade, which allows the blade to be withdrawn.

55 Although I have herein described rather suc-

cinctly the nature and use of my invention so that persons skilled in the art will have no difficulty apprising themselves of the teachings thereof and, inasmuch as the disclosure is susceptible of various alterations, modifications, and improvements, I hereby reserve the right to all modifications, alterations, and improvements falling within the scope and spirit of my invention, as well as any modifications that are embraced suggestively in the accompanying drawings, and any 10 that may come within the purview of the foregoing description; my invention to be limited only by the appended claims.

Having thus disclosed and revealed my invention, what I claim as new and desire to secure 15 by Letters Patent is:

1. A razor blade handle attachment, comprising a pair of handle elements, of substantially similar configuration secured together in face-to-face relationship, defining therebetween a blade 20 confining slot extending inwardly from one end intermediate the top and bottom surfaces of the handle, one of said handle elements being provided with lip portions at one end thereof defining an intermediately recessed portion, the other 25 of said handle elements being provided with complementary shoulder cuts adapted to contact intimately the said lip portions and further provided with an intermediate lip portion to fit the said recessed portion resulting in said blade 30 confining slot, a bore at the lower edge of the said handle attachment merging with the said blade confining slot and provided with a keyway, a locking tumbler provided with a key slidably operative in the said keyway and adapted to slide in the said bore and further provided with a binding edge positioned in transverse relationship to the cutting edge of a razor blade, pressure means urging the said locking tumbler into nicking engagement with the cutting edge of the 35 said razor blade, and a blade removably insertable with its sharp edge toward the said locking tumbler in the said blade confining slot, the said locking tumbler being provided with two facets 40 at its top defining a binding edge to engage transversely the sharp edge of the said blade and nick the same to lock it in place firmly.

2. A razor blade handle attachment, comprising a pair of handle elements, of substantially similar configuration secured together in face-to-face relationship, defining therebetween a blade confining slots extending inwardly from one end intermediate the top and bottom surfaces of the handle, one of said handle elements being provided with lip portions at one end thereof defining an intermediately recessed portion, the other 50 of said handle elements being provided with complementary shoulder cuts adapted to contact intimately the said lip portions and further provided with an intermediate lip portion to fit the said recessed portion resulting in said blade 55 confining slot, a bore at the lower edge of the said handle attachment merging with the said blade confining slot and provided with a keyway, a locking tumbler provided with a key slidably operative in the said keyway and adapted to slide in the said bore and further provided with a binding edge positioned in transverse relationship to the cutting edge of a razor blade, pressure means urging the said locking tumbler into nicking engagement with the cutting edge of the 60 said razor blade, and a blade removably insertable with its sharp edge toward the said locking tumbler in the said blade confining slot, the said locking tumbler being provided with two facets at its top defining a binding edge to engage transversely the sharp edge of the said blade and nick the same to lock it in place firmly.

of the said handle attachment merging with the said blade confining slot and provided with a keyway, a locking tumbler provided with a key slidably operative in the said keyway and adapted to slide in the said bore and further provided with a binding edge positioned in transverse relationship to the cutting edge of a razor blade, screw pressure means urging the said locking tumbler into nicking engagement with the cutting edge of the said razor blade, and a blade removably insertable with its sharp edge toward the said locking tumbler in the said blade confining slot, the said locking tumbler being provided with two facets at its top defining a binding edge to engage transversely the sharp edge of the said blade and nick the same to lock it in place firmly.

3. A razor blade handle attachment, comprising a pair of handle elements, of substantially similar configuration secured together in face-to-face relationship, defining therebetween a blade confining slot extending inwardly from one end intermediate the top and bottom surfaces of the handle, one of said handle elements being provided with lip portions at one end thereof defining an intermediately recessed portion, the other of said handle elements being provided with complementary shoulder cuts adapted to contact intimately the said lip portions and further provided with an intermediate lip portion to fit the said recessed portion resulting in said blade confining slot, a bore at the lower edge of the said handle attachment merging with the said blade confining slot and provided with a keyway, a locking tumbler provided with a key slidably operative in the said keyway and adapted to slide in the said bore and further provided with a binding edge positioned in transverse relationship to the cutting edge of a razor blade, pressure means urging the said locking tumbler into nicking engagement with the cutting edge of the said razor blade, and a blade removably insertable with its sharp edge toward the said locking tumbler in the said blade confining slot, the said locking tumbler being provided with two facets at its top defining a binding edge to engage transversely the sharp edge of the said blade and nick the same to lock it in place firmly.
